UNITED STATES PATENT OFFICE.

MAX ZIEHLKE, OF LINTON, NORTH DAKOTA.

DOOR FASTENER.

Application filed April 2, 1923. Serial No. 629,305.

To all whom it may concern:

Be it known that I, MAX ZIEHLKE, a citizen of the United States, residing at Linton, in the county of Emmons and State of North Dakota, have invented a certain new and useful Door Fastener, of which the following is a specification.

The object of my invention is to provide a door fastener of simple, durable, and comparatively inexpensive construction, whereby it may be manufactured and marketed at a comparatively low cost.

More particularly, my invention relates to a door fastening device for locking sliding doors used in barns, garages, warehouses, and the like.

Still a further object is to provide a locking structure for sliding doors which, when removed, will not interfere with the sliding movement of the doors.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 is a side elevation of a portion 30 of a building with a pair of sliding doors shown thereon with my improved door fasteners.

Figure 2 is a sectional view taken on line 2—2 of Figure 1.

Figure 3 is a sectional view taken on line 3—3 of Figure 1.

Figure 4 is a front elevation of the strap member forming a part of my fastener.

In the accompanying drawings, I have 40 used the reference numeral 10 to indicate generally the walls of a building. A pair of sliding door members 11 and 12 are provided, which are suspended from a track 13 by means of rollers 14.

A door fastener device is used for each of 45 the door members 11 and 12. In the wall 10, adjacent to the sides of the doors 11 and 12, I provide a recess 15 for receiving a keeper or catch member 16. The catch member is secured in position by means of the screws 17.

The upper surface of the catch member is substantially flush with the outer surface of the wall 10 so that when the doors 11 and

12 are slid to their open position, the catch member will not interfere therewith.

Fixed at the door members 11 and 12 are the hooks or staples 18. A strap member 19 forms the main part of my door fastener and cooperates with the keeper 16 for completing the door fastener. The strap member 19 is provided with a portion 20 arranged at right angles to the main part of the strap 19.

The portion 20 terminates into a curved 65 portion or hook member 21. The hook member 21 is designed to coact with the catch or keeper 16 as will be hereinafter more fully set forth.

The strap member is provided with a slot 70 22 through which may be extended the hook 18. The strap member 19 has an inclined portion 23 to which is secured a chain or other suitable flexible element 24. The free end of the chain 24 is secured to the door 75 by means of a staple 25.

In this connection, it may be mentioned that a complete door fastener is used for each of the door members 11 and 12.

The strap member 19 has a locking element 26 thereon which is pivotally mounted on the rivet 27. The locking element 26 is provided with a finger engaging piece 28. The locking element 26 is designed to extend into the hook or staple 18, as clearly shown 85 in Figures 1 and 2 of the drawings.

I will now describe in detail the operation of my door fastener. The strap member 19 which forms one part of the fastener is secured to the door 11 by means of the chain 90 24.

The strap member is moved to the position shown in dotted lines in Figure 2 of the drawings, and when in this position, the hook member 21 may be slipped in position 95 under the keeper 16. The locking element 26 is then in the position shown in Figure 4 of the drawings.

The strap member is then moved towards the door so that the staple or hook 18 will 100 project through the slot 22. The locking element 26 is then moved so that the hook portion thereof will project into the strap 18. The right angle portion 20 will rest against the edge of the door member. 105

When the locking element 26 is in closed position, then the entire strap member will be held against undesired movement and

the catch member and hook 21 will cooperate for holding the door closed.

In this connection, it may be mentioned that a lock may be extended over the staple 18 after the strap member 19 is in position, as shown in Figure 4, for holding the strap member in position.

It will be seen that the strap member 19 is free to swing from the chain 24 when not in use. When the strap member 19 is not in use, then the door members may be moved over the catch members 16 without any interference therefrom.

It will be seen that I have provided a very efficient door fastener for sliding doors. A door fastener is provided which is very desirable. I am able to move one of the doors without interfering with or unlocking the other door.

Some changes may be made in the construction and arrangement of the various parts of my invention, without departing from the real spirit and purpose of my invention and it is my intention to cover by

my claims, any modified forms of structure 25 or use of mechanical equivalents, which may be reasonably included within their scope.

I claim as my invention:

In combination with a building having a door opening and sliding doors therefor, a door fastener including a strap member having a portion formed at right angles thereto and terminating in a curved portion, said strap member having a slot therein, a flexible element for securing said member to the door, a hook mounted on said door arranged to extend through said slot, a catch member mounted on the wall of the building adjacent to the door opening, said catch member being recessed into the wall for permitting the door to slide thereover, the curved portion of said strap member being capable of engaging the catch member and a pivoted locking element for holding the strap member in position.

Des Moines, Iowa, March 20, 1923.

MAX ZIEHLKE.
